(57) **CLAIM**

The ornamental design for a load cell for a scale, as shown and described.

DESCRIPTION

FIG. 1 is a perspective view of the load cell;

FIG. 2 is a front elevation view of the FIG. 1 embodiment;

FIG. 3 is a rear elevation view of the FIG. 1 embodiment;

FIG. 4 is a left side elevation view of the FIG. 1 embodiment;

FIG. 5 is a right side elevation view of the FIG. 1 embodiment; and,

FIG. 6 is a top plan view of the FIG. 1 embodiment, the bottom plan view not being shown, as it does not form part of the claimed design.

The broken line showing of a terminal for attaching cable plugs in FIGS. 1, 2 and 4-6 is included for the purpose of environment and forms no part of the claimed design.
